UNITED STATES PATENT OFFICE.

FRANK J. SCHALOW, OF EAST NEW YORK, N. Y., ASSIGNOR OF ONE-HALF TO AUGUST H. SCHALOW, OF EAST NEW YORK, N. Y.

HAT-CROWN-CREASE-RETAINING DEVICE.

1,387,015.

Specification of Letters Patent.

Patented Aug. 9, 1921.

Application filed July 17, 1920. Serial No. 396,900.

To all whom it may concern:

Be it known that I, FRANK J. SCHALOW, a citizen of the United States, and residing at East New York, in the county of Kings 5 and State of New York, have invented certain new and useful Improvements in Hat-Crown-Crease-Retaining Devices, of which the following is a specification, such as will enable those skilled in the art to which it 10 appertains to make and use the same.

This invention relates to devices for retaining a crease in the crown of felt or other soft hats, and the object thereof is to provide an improved device of this class which 15 is simple in construction, efficient in use and comparatively inexpensive; and with this and other objects in view the invention consists in a device of the class specified, constructed and operated as hereinafter described and claimed.

The invention is fully disclosed in the following specification, of which the accompanying drawing forms a part, in which the separate parts of my improvement are 25 designated by suitable reference characters in each of the views, and in which:—

Figure 1 is a side view of a hat with part of the construction broken away and showing the use of my improved crease retaining device;

Fig. 2 a section on the line 2—2 of Fig. 1;

Fig. 3 a side view of the crease retaining device;

Fig. 4 an end view thereof; and,

Fig. 5 a back view thereof.

In the drawing forming part of this specification I have shown what is known as a soft hat 5 provided with a crown 6, the central top portion of which is folded 40 inwardly as shown at 7 to form the desired crease therein, and at 8 I have shown my improved crease retaining device in use.

The crease retaining device is formed from sheet metal, celluloid, rubber or other more 45 or less elastic material and is oblong and approximately rectangular in form, and comprises a hollow cylindrical back portion 9 in the back part of which is a thumb and finger recess 10, and the front part thereof 50 is open longitudinally as shown at 11 to form a narrow slot, the opposite side walls of which are provided with projecting side flanges or plates 12 which, in the form of construction, shown are normally slightly 55 divergent.

In the use of this device the crown of the hat is folded centrally and forwardly and backwardly to form the desired crease and the sides of the folded part of the crown are brought together, and the side flanges or 60 plates 12 of the crease retaining device are passed upwardly thereover so that the folded part of the crown extends downwardly through the crease retaining device and into the thumb or finger recess 10, after which 65 said folded part of the crown at 13 is grasped by a thumb and finger and said drawn part of the crown is folded downwardly tightly into the crease retaining device. This operation packs or folds a part of the crown 70 of the hat in the cylindrical back portion 9 of the crease retaining device, and said device securely grasps and holds the folded part of the crown in the desired position.

My improved hat crown crease retaining 75 device is not limited to any specific material in the construction thereof, nor to any exact dimensions thereof, all that is necessary in this connection being that the device be made of spring material and that the side 80 portions of the device be so formed as to securely grasp and hold the folded part of the crown of the hat, and this operation is made more sure and positive by the fact that the side flanges or plates 12 normally 85 converge inwardly toward the slot in the cylindrical back part 9 of the device with the side walls of which slot the said wings or plates are connected. With this construction, the spring force of the cylindrical back 90 part 9 of the device is added to that of the side plates or flanges 12 of the device which press on the opposite sides of the fold of the crown of the hat, and this causes the device to securely grasp and hold said fold 95 when said device is applied, as hereinbefore described.

Having fully described my invention, what I claim as new and desire to secure by Letters Patent, is:—

1. A hat crown crease retaining device composed of spring sheet metal and comprising a cylindrical portion in one side of which is a narrow longitudinal slot, the side walls of which are provided with projecting 105 flanges or plates, the cylindrical portion being also provided opposite the slot therein with a longitudinal thumb and finger recess.
2. A hat crown crease retaining device composed of a sheet of spring material and 110

100

comprising a cylindrical back part provided in the front side thereof with a narrow longitudinal slot, the side walls of which are provided with projecting and slight divergent side flanges or plates, the cylindrical back part being also provided in the side thereof opposite the slot therein with a large thumb and finger recess.

In testimony that I claim the foregoing as my invention I have signed my name in presence of the subscribing witnesses this 14th day of July, 1920.

FRANK J. SCHALOW.
